UNITED STATES PATENT OFFICE.

HIRAM HOLDEN, JR., OF SPENCER, MASSACHUSETTS.

TENSION DEVICE FOR SEWING-MACHINES.

SPECIFICATION forming part of Letters Patent No. 277,281, dated May 8, 1883.

Application filed September 15, 1882. (Model.)

To all whom it may concern:

Be it known that I, HIRAM HOLDEN, Jr., of Spencer, in the county of Worcester and State of Massachusetts, have invented certain new 5 and useful Improvements in Tension Devices for Sewing-Machines, of which the following is a full, clear, and exact description.

My improvements relate to devices for wax and dry thread sewing-machines, and have for 10 their object to insure the tightening of the thread in the work, and to prevent cutting or breaking of the thread.

The invention consists in devices fitted to 15 act automatically in drawing and tightening the thread, as hereinafter described and claimed.

Reference is to be had to the accompanying drawings, forming part of this specification, in which similar letters of reference indicate corresponding parts in all the figures.

20 Figure 1 is a side elevation of the improved tension devices as applied for using a wax-thread. Fig. 2 is a similar view, showing the device as applied for using a dry thread. Fig. 3 is a face view of the tension mechanism. 25 Fig. 4 is a detailed view of the slotted stud, within which one end of the take-up arm is guided.

30 A is the arm of the machine. a is the awl-bar; b, the needle-bar; c, the presser-foot; d, thread-guide; e, cast-off bar, and f wax-dish.

The tension devices are carried by a plate, g, that is formed for attachment to the arm of the machine in either of the positions shown.

35 h is the tension-wheel on a stud-post, i, that carries a washer and spiral spring, k, and thumb-nut l for adjusting the tension of the spring.

40 m is a spring take-up arm, formed with an eye at its outer end, and coiled at its inner end around a stud, n, which has a set-nut, o.

p is a guide-pin, and q is a guide-eye on the plate g.

45 r is a stud or post on the plate, carrying a regulating-screw, s, that limits the backward movement of the arm m, the stud being slotted to allow the arm to bear on the screw, and t is a set-nut on the screw s.

50 In threading the tension for wax-thread machines, the thread passes, as shown in Fig. 1, from the wax-dish f through a guide, u, fastened on stud-post i, thence to and around ten-

sion-wheel h to pin p, through eye on the end of spring-arm m, and thence through guide-eye q to the thread-guide d and needle. For dry thread, the thread passes, as in Fig. 2, from spool to guide u, fastened on stud-post i, thence to and around tension-wheel h to pin p, through eye on the end of spring-arm m, and thence through guide-eye q to thread-controller y and top of needle-bar, and thence to bottom of 60 needle-bar and needle, as shown in drawings. The tension of wheel h is regulated by turning thumb-nut l, and the take-up spring m is adjusted by the stud n, as required, to throw spring-arm back to screw s, and fixed in place 65 by nut o. The turning inward or outward of the screw s limits the amount of thread taken up by the arm m, while its position of adjustment is fixed by the nut t.

In operation on wax-thread machines, as the 70 needle descends it takes the thread and draws it down through the work and plate to the extent required to form the loop and cast it from the needle. The spring-arm m is drawn forward and the thread drawn from tension-wheel 75 h. Then, as the needle ascends to take the thread, the spring-arm m moving backward to screw s, the thread is not drawn back with the needle, but a loop is left for the cast-off to hold until the needle again descends. In dry- 80 thread machines, as the needle-bar rises the spring-arm m is drawn forward and the thread drawn from tension-wheel h. Then, as the needle descends, the spring-arm m moves backward to the screw s and leaves sufficient thread 85 to form the loop for the shuttle. The loop is left of the same length at every movement. Tight stitches are thus insured, and there is no risk of breaking the thread.

The center surface of tension-wheel h is 90 roughened or double-cut, so that it is impossible for the thread to slip around the wheel, thus getting all the friction that is produced by thumb-nut l.

Having thus fully described my invention, I 95 claim as new and desire to secure by Letters Patent—

1. The combination, with the tension-wheel h and the plate g, having the slotted stud r, provided with the adjusting-screw s t, of the 100 spring take-up arm m, the said arm being arranged to move in the slot of said stud and to

receive the action of the screw *s*, substantially as and for the purpose set forth.

2. The combination, with the tension-wheel *h* and the plate *g*, having the slotted stud *r*, provided with the adjusting-screw *s t*, of the spring take-up arm *m* and the stud *n*, to which the said arm is attached, and which has a set-

nut, *o*, substantially as and for the purpose set forth.

HIRAM HOLDEN, JR.
